US0D1059829S

(12) **United States Design Patent** (10) Patent No.: **US D1,059,829 S**
(45) Date of Patent: ** Feb. 4, 2025

(54) **STORAGE BOX**

- (71) Applicant: **Makita U.S.A., Inc.**, La Mirada, CA (US)
- (72) Inventors: **Andrew Camp**, La Mirada, CA (US); **Marc Tappeiner**, Santa Barbara, CA (US); **Jeremy Allan**, Santa Barbara, CA (US); **Ethan W. Franklin**, Santa Barbara, CA (US); **Cameron Putnam**, Santa Barbara, CA (US); **John Grant**, Middletown, OH (US); **Amin Dahrehsobh**, Santa Barbara, CA (US); **Kenneth Hefley**, La Mirada, CA (US); **Keisuke Kato**, La Mirada, CA (US); **Brent Withey**, La Mirada, CA (US); **Austin Donoghue**, La Mirada, CA (US); **Nathan Santos**, La Mirada, CA (US)

- (73) Assignee: **Makita U.S.A., Inc.**, La Mirada, CA (US)

(**) Term: **15 Years**

(21) Appl. No.: **29/863,574**

(22) Filed: **Dec. 20, 2022**

Related U.S. Application Data

(63) Continuation-in-part of application No. 17/966,454, filed on Oct. 14, 2022.

CLAIM

The ornamental design for a storage box, as shown and described.

DESCRIPTION

FIG. 1 is a top perspective view of a second embodiment of a new design for a storage box;
FIG. 2 is a top view thereof;
FIG. 3 is a bottom view thereof;
FIG. 4 is a right side view thereof;
FIG. 5 is a left side view thereof;
FIG. 6 is a front view thereof;
FIG. 7 is a back view thereof;
FIG. 8 is a cross-section view thereof as indicated in FIG. 2;
FIG. 9 is another cross-section view thereof as indicated in FIG. 2;
FIG. 10 is a cross-section view thereof as indicated in FIG. 3;
FIG. 11 is another cross-section view thereof as indicated in FIG. 3;
FIG. 12 is another top perspective view thereof;
FIG. 13 is an enlarged view thereof as indicated in FIG. 12;
FIG. 14 is another top perspective view thereof;
FIG. 15 is an enlarged view thereof as indicated in FIG. 14;
FIG. 16 is a bottom perspective view thereof;
FIG. 17 is an enlarged view thereof as indicated in FIG. 16;
FIG. 18 is another bottom perspective view thereof; and,
FIG. 19 is an enlarged view thereof as indicated in FIG. 18.
The dash-dash broken lines depict portions of the storage box that form no part of the claimed design. The dash-dot dot-dash broken lines depict cross-section and enlargement boundary limits that form not part of the claimed design.
